DESIGN FOR A CHAIR

Walter J. Forster, St. Louis, Mo., and Raymond F. Loewy, New York, N. Y., assignors to Curtiss-Wright Corporation (St. Louis Div.), a corporation of Delaware

Application May 16, 1939, Serial No. 85,021

Term of patent 3½ years

To all whom it may concern:

Be it known that we, Walter J. Forster and Raymond F. Loewy, citizens of the United States, residing at St. Louis, State of Missouri, and New York, in the county of New York and State of New York, respectively, have invented a new, original, and ornamental Design for Chairs, of which the following is a specification, reference being had to the accompanying drawing, forming part thereof.

Fig. 1 is a front perspective view, and Fig. 2 is a rear perspective view of a chair showing our new design.

We claim:

The ornamental design for a chair as shown.

WALTER J. FORSTER.
RAYMOND F. LOEWY.
